UNITED STATES PATENT OFFICE

2,047,812

APPARATUS FOR MAKING RIMS

Allen B. Wilson, Evanston, Ill., assignor to Acme Steel Company, Chicago, Ill., a corporation of Illinois

Application June 13, 1934, Serial No. 730,456

15 Claims. (Cl. 153—21)

This invention relates to improvements in apparatus for making rims and, in particular, to apparatus adapted for making metallic rims of polygonal form which are adapted to fit over the ends of containers of corresponding polygonal cross-section, such as the container and rim described and claimed in the co-pending application of Chester M. MacChesney Serial No. 730,413, filed June 13, 1934. The principal object of the invention is to provide an improved form of apparatus adapted for use in forming a metallic rim of polygonal form by applying pressure to a metallic rim which is initially formed as a circular rim of sheet metal or the like. Another object of the invention is to provide apparatus adapted to exert pressure radially upon an annular metallic rim for the purpose of causing the rim to assume a polygonal shape. Still another object of the invention is to provide improved apparatus adapted to receive an annular metallic rim provided with an inwardly extending transversely corrugated flange and to convert this rim into a member of polygonal form having inwardly extending angularly disposed flanges. Another object of the invention is to provide apparatus adapted to receive the annular rim and to exert radial pressure on the rim both inwardly and outwardly for the purpose of flattening the metal of the rim between points which become the apices of a resulting polygonal rim. Other objects relate to various features of construction and arrangement which will appear more fully hereinafter.

The nature of the invention will be understood from the following specification taken with the accompanying drawings, in which one embodiment of the improved apparatus is illustrated.

In the drawings,

Fig. 1 shows a perspective view of a section of strip steel or the like adapted to be used in forming an annular metallic rim to be operated upon by the apparatus of the present invention;

Fig. 2 is a perspective view of the metallic strip shown in Fig. 1 after it has been operated upon to form an inwardly extending transversely corrugated flange and to provide holes along the bottom of the strip;

Fig. 3 is a perspective view of a complete circular rim formed by uniting the ends of a strip having the construction illustrated in Fig. 2;

Fig. 4 is a perspective view of the complete rim of polygonal shape which is formed from the rim illustrated in Fig. 3 with the use of the apparatus of the present invention;

Fig. 5 shows an enlarged top plan view of a

portion of the completed rim illustrated in Fig. 4; Fig. 6 shows a vertical axial section through the improved apparatus of the present invention, which is adapted to form the rim illustrated in Fig. 4 by operating upon the circular rim illustrated in Fig. 3;

Fig. 7 shows an enlarged detail section through a portion of the apparatus illustrated in Fig. 6, the section being taken on the line 7—7 of Fig. 9;

Fig. 8 shows a vertical section taken on the line 8—8 of Fig. 6; and

Fig. 9 shows a partial view similar to that of Fig. 8 with the pressure heads of the apparatus in the relative positions which they occupy in the final stage of compressing the rim illustrated in Fig. 3 to cause it to assume the polygonal form shown in Fig. 4.

The present invention is adapted to produce a metallic rim 26 of polygonal form, as shown in Fig. 4, having a plurality of depending portions 26^a adapted to conform to and fit against the outer surfaces of the walls of a container of similar cross-section, and also a series of inwardly extending transversely corrugated flanges 26^b which overlie and normally engage the outer surface of the end wall of the container. Before employing the apparatus of the present invention, a circular rim is first formed from an elongated strip 30 of steel or the like, a portion of which is shown in Fig. 1. Having provided the strip 30 of the desired width and length, it is operated upon by suitable dies and rolls, preferably by the method described and claimed in the United States patent of Messrs. Fork and Kronquest No. 1,771,955, dated July 29, 1930, thereby producing the structure illustrated in Fig. 2, in which the metal strip has assumed the form of an upright body portion 30^a provided with a transverse flange 30^b having formed therein a series of transverse parallel corrugations 30^c. At the same time that the corrugated flange 30^b is formed, the lower edge of the body portion 30^a is punched to provide a series of apertures 31 which, when the completed rim is applied to a container, are adapted to be engaged by nails or the like for holding the rim in place.

After forming the flanged strip illustrated in Fig. 2, the required length of material of this formation is bent into the form of a circular rim 32, as shown in Fig. 3, and the overlapping ends of this rim are secured together by rivets 33 or other fastening means. During the process of bending this flanged strip into the form of the circular rim 32, the corrugations 30^c contract toward their rear extremities, thereby causing adjacent cor-

rugations to converge inwardly and permitting the flange to adjust itself to the circular form shown in Fig. 3 without causing the metal of the flange to bend or buckle or to depart from its 5 position in a plane extending transversely to the annular depending body portion 30^a of the rim. Having formed the circular flanged rim illustrated in Fig. 3, this rim is operated upon by the apparatus of the present invention, according to 10 the method which is described and claimed in the co-pending application of Chester M. MacChesney and Allen B. Wilson Serial No. 730,412, filed June 13, 1934, thereby compressing certain portions of the rim and expanding other portions to 15 produce the completed rim 26 of polygonal form which is shown in Fig. 4. During this process, the corrugated annular flange 30^b assumes the form 20 of a series of connected corrugated flanges 26^b having a polygonal relationship, in this instance, the form of an octagon, and the metal of the depending portion 30^a of the rim assumes the form 25 of the several connected portions 26^a of the rim which are united with each other in the form of a polygon of true octagonal shape. As the flanges 26^b are caused to assume the polygonal 30 relationship, the inner ends of the corrugations adjacent the apices of the polygon become still narrower than they were in the circular rim but the inner ends of those corrugations which 35 occupy intermediate positions become wider and these corrugations may assume substantially the parallel relationship they had in the straight flanged strip, shown in Fig. 2 from which the circular rim was formed.

35. The improved apparatus of the present invention which is adapted to produce the polygonal rim above described, is illustrated in Figs. 6, 7, 8 and 9, where it is shown as comprising a frame 35 having a horizontal table 36 projecting outwardly therefrom and having an upright member 37 which carries a stationary cam spindle 38 arranged to project in a horizontal direction over the table 36. The spindle 38 supports a disk 40 having a hub 40^a provided with a bushing 41 which is journaled on the spindle so that the disk 40 is capable of being moved bodily inward from the position shown in Fig. 6 toward the upright member 37. The disk 40 carries around its outer edge a series of brackets 42 which form the 45 heads of a series of cylinders 43, one of which is mounted upon each bracket. These cylinders are closed at their outer ends by heads 44 through which connectors 45 establish communication from the interiors of these cylinders to a pipe 46 leading from a source of supply of compressed fluid such as air or steam. The connections to these cylinders are controlled by a valve 47 so that compressed fluid may be admitted thereto for the purpose of actuating the pistons 48. Other 50 connectors 45^a are adapted to establish communication from the source of compressed fluid supply with the inner ends of the cylinders 43 so that the pistons 48 may be retracted after they have been moved inwardly by the admission of 55 compressed fluid through the connectors 45. These pistons are connected to piston rods 49 which are slidably mounted in the brackets forming the inner heads of the cylinders and these piston rods carry at their inner ends, outside of 60 the cylinders, the T shaped pressure heads 50 which are adapted to be moved inwardly by the action of the compressed fluid to engage the outer surfaces of the circular hoop 32 when this hoop is placed in the apparatus for the purpose of being 65 transformed into octagonal shape. The ends 70 of the arms of the T shaped heads 50 are slightly beveled at the corners which engage the circular hoop or rim, as shown at 50^a, and they are also beveled transversely along their inner edges, as shown at 50^b in Fig. 7 so that when these heads 75 are actuated they engage only those portions of the metal rim which lie in proximity to the transverse corrugated flange formed thereon. Upon the admission of compressed fluid to these cylinders 43, all of the pressure heads 50 are actuated simultaneously.

When the circular hoop 32 is placed in the apparatus shown in Figs. 6, 7 and 8, it is supported on the inner side of the body portion 30^a of the rim by means of a series of inner pressure heads 51 which are mounted on plungers 52 arranged to slide in radial guideways 53 carried by the disk 40. These guideways are undercut so that the plungers 52 are retained in place therein and at their inner ends the plungers are provided with 20 rollers 54 which are maintained in contact with the tapered cam faces 38^a of the spindle 38 by coil springs 52^a mounted in cylindrical recesses formed in the ends of the plungers and engaging brackets 52^b secured to the disk 40. When the 25 disk 40 is moved longitudinally of the cam spindle 38, the tapered cam faces 38^a, engaging the rollers 54, cause the plungers 52 to be projected radially outward in their guideways, thus causing the inner pressure heads 51 to move outwardly against the surrounding metal rim and thereby assist in imparting to this rim the final octagonal shape shown in Fig. 4. The pressure heads 51 are triangular in radial cross-section and have 30 opposite angularly disposed faces 51^a which are inclined toward each other at an angle corresponding to that between the faces of two adjacent side walls 16 of the container to which the rim is to be applied. The faces 51^a of the pressure heads 51 are beveled outwardly away 40 from the axis of the spindle 38 adjacent their rear edges which are disposed in proximity to the plungers 52, as shown at 51^b in Fig. 7, so that when the rim is completed by being pressed against and expanded outwardly by the pressure 45 heads 51, the sections 26^a of the completed rim are flared outwardly to a slight extent as shown at 26^c in Figs. 4 and 7.

The movement of the disk 40 longitudinally of the spindle 38, which brings about the outward 50 radial movement of the inner pressure heads 51, is effected by means of a pressure plate or disk 55 which is mounted with its axis coincident with the axis of the spindle 38. The disk 55 is provided with a central recess 55^a which is adapted to receive the tapered extremity of the spindle 38 when the disk 55 is moved to its extreme position toward the right, as viewed in Fig. 6, during the process of forming the rim, and the disk is carried by a rod 56 formed in two sections which have their inner portions screw-threaded and engaged by a turnbuckle 57 so that the effective length of the rod may be varied to compensate for variations in the diameters of the sheet metal 60 hoops being operated upon by the apparatus. The rod 56 is pivotally connected by a pin 58 with a piston rod 59 by which the plate or disk 55 is actuated. This piston rod is connected to a piston 60 located in a cylinder 61 which is supported on the table 36 by means of an angle bar 62. Compressed fluid, such as compressed air or the like, may be admitted to the inner and outer 65 ends of the cylinder 61 through the pipes 63 and 64, respectively, which may be controlled by 70 valves in order to move the plate or disk 55 in 75

either direction, as desired. The disk 55 is held against rotation and is supported by a guide rod 65 which is connected to the lower portion of the plate or disk and arranged to slide in bearing blocks 66 carried by the table 36. The lower portion of the plate or disk 55 is provided with a projecting ear 55^b engaged by a rod 67 which is held in fixed relation to the disk 55 but which has a sliding engagement with the disk 40 through an aperture 40^b formed therein. The inner end of this rod 67 is threaded for engagement by lock nuts 68 which may be adjusted to regulate the normal position of the disk 55 with respect to the disk 40. When the disk or plate 55 is retracted by the admission of compressed fluid to the inner end of the cylinder 61, the disk 40 is moved outwardly upon the cam spindle 38 by reason of the connection established between the two disks by the rod 67, and when the disk 55 moves inwardly toward the disk 40, the rod 67 is permitted to slide freely in the aperture 40^b to project rearwardly beyond the disk 40.

In the operation of the apparatus heretofore described, the circular rim is first placed over the inner pressure heads 51 with the corrugated flange 30^b extending in a vertical direction adjacent the front faces of these pressure heads. Upon admitting compressed fluid to the outer end of the cylinder 61, the pressure plate or disk 55 is moved inwardly toward the disk 40 until it engages the vertically extending corrugated flange 30^b of the rim and then, upon continued movement of the pressure plate 55, the disk 40 and all parts carried thereby are moved bodily along the spindle 38 toward the frame member 37 with the result that the plungers 52 are projected outwardly, thereby causing a corresponding outward radial movement of the pressure heads 51, thereby expanding the metal of the circular rim 32 and tending to cause it to assume the final octagonal shape shown in Fig. 4. The engagement of the pressure heads 51 of triangular cross-section with the inner surface of the metallic rim may be sufficient to complete the formation of the octagonal shape in those parts of the rim which are removed from the transverse flange 30^b but, owing to the stiffness of the rim in the region of this corrugated flange, it is desirable to bring the outer pressure heads 50 into play for the purpose of flattening out those portions of the metal rim which are located between the apices of the inner pressure heads 51, it being noted that the inner pressure heads are each mounted to move along a radial line located midway between the radial paths of movement of the two next adjacent outer pressure heads 50. The inward movement of these pressure heads 50 flattens the metal of the rim, adjacent the corrugated flange, radially inward against the faces of the inner pressure heads 51 and thus assists the action which is brought about by the outward radial movement of the inner pressure heads. In order to cause the inward movement of the pressure heads 50 to take place automatically after a predetermined movement of the disks 55 and 40, a block 70 is mounted on a bracket 71 carried by the plate 37 and this block has an inclined face 70^a adapted to engage the valve stem 47^a and open the valve 47 so that the heads 50 may be caused to move inwardly in the desired time relation to the outward movement of the heads 51. Because of the desirability of forming a sharp angle between each two adjacent sections of the octagonal rim, the apices 51^c of the inner pressure heads are preferably arranged to project

slightly outward beyond the point of intersection of planes containing the faces 51^a of the pressure head and this slight outward projection cooperates with the bevels 50^a formed at the ends of the outer pressure heads to cause a slight outward projection of the metal of the octagonal rim at the points of connection of two adjacent sections 26^a of the rim. Because of the action of the inner pressure heads in expanding the metal of the rim adjacent the apices 26^d of the rim between two adjacent sections thereof, and the action of the outer pressure heads in flattening out the metal between these apices in the rim, the transversely extending corrugated flange is subjected to forces tending to contract it adjacent the apices 26^d and to expand it at points midway between these apices and it has been found that by reason of the corrugation of the transverse flange of the rim, prior to imparting the octagonal or other polygonal shape thereto, the various portions of the transverse flange adjust themselves automatically to these varying forces tending to distort different parts of the flange in different ways and the flange thus maintains its position in a plane extending transversely to the axis of the disks 40 and 55 inasmuch as the corrugations at points midway between the apices of the rim radially expand at their inner extremities, as shown at 26^e, until the corrugations are substantially parallel, while at 30 points adjacent the apices of the rim these corrugations are contracted more closely upon each other as shown at 26^f with their inner extremities lying in closer relation than their outer extremities. This action of the corrugated flange 35 of the rim is assisted by the engagement therewith of the pressure plate 55 and it will be observed that the action of the pressure plate 55, when it projects the corrugated flange against the vertical faces of the inner pressure heads 51, 40 also serves to project the body portion of the rim upwardly, over the tapered surfaces 51^b of the inner pressure heads, thereby imparting to the edge of the rim the flared portion 26^c heretofore referred to. Owing to the independent fluid connections which are made with the cylinders 43, the outer pressure heads 50 may be operated to move inwardly simultaneously with the outward movement of the inner pressure heads 51 or the inward movement of the outer pressure heads 50 may be caused to take place at any other time which is adapted to bring about the best results in the formation of the rim.

Although one form of the improved rim forming apparatus has been shown and described by way of illustration, it will be understood that it may be constructed in various other embodiments coming within the scope of the appended claims.

I claim:

1. The combination in apparatus for forming hexagonal rims, of an annular series of pressure members each having an angular outer edge adapted to fit an apex of a hexagon, said pressure members being adapted to extend within a circular metallic rim, and means for moving said pressure members and said annular rim longitudinally of the axis of said rim and thereby causing outward movement of said pressure members.

2. The combination in apparatus for forming polygonal rims, of an annular series of pressure members each having an angular outer edge, said pressure members being adapted to extend within an angular metallic rim, means for moving said pressure members radially outward, a second

series of pressure members located on the outer side of said rim, each of said outer pressure members occupying a position between two of said first named pressure members, and means 5 for effecting inward movement of said second named pressure members.

3. The combination in apparatus for forming a polygonal rim, of a series of inner pressure members each having an angular outer edge, said pressure members being adapted to extend within a 10 surrounding metallic rim, an outer series of pressure members located on the outer side of said rim and arranged in staggered relation to said inner pressure members, each of said outer pressure members having a straight inner edge to coact 15 with said rim, and means for effecting outward movements of said inner pressure members and inward movements of said outer pressure members.

20 4. The combination in apparatus for forming a hexagonal rim, of means adapted to extend within and support an annular metallic rim, a series of pressure members spaced uniformly around the outside of said rim, said pressure members having 25 flat inner edges, and means for moving said pressure members inwardly to impart a hexagonal form to said rim.

5. The combination in apparatus for forming a polygonal rim, of means adapted to extend within 30 and support an annular metallic rim, a series of pressure members spaced uniformly around the outside of said rim, said pressure members having flat inner edges, and fluid pressure means for moving said pressure members inwardly against 35 said rim.

6. The combination in apparatus for forming a polygonal rim, of means adapted to extend within and support an annular metallic rim, a series of pressure members spaced around the outside of 40 said rim, said pressure members having flat rim-engaging surfaces beveled at their ends, and means for moving said pressure members inwardly against said rim.

7. The combination in apparatus for forming a 45 polygonal rim having a flare along one edge, of a series of inner pressure members adapted to extend within and support a cylindrical metallic rim, said pressure members being flared at one edge transversely to the axis of said rim, means 50 for moving said pressure members and said rim longitudinally of the axis of said rim to cause said flared portions of said pressure members to produce an annular flare on said rim, and means actuated by said movement of said pressure members for causing said pressure members to move 55 radially outward to impart a polygonal form to said rim.

8. The combination in apparatus for forming a polygonal rim having a flare along one edge, of a 60 series of inner pressure members adapted to extend within and support a cylindrical metallic rim, said pressure members being flared at one edge transversely to the axis of said rim, means 65 for moving said pressure members and said rim longitudinally of the axis of said rim to cause said flared portions of said pressure members to produce an annular flare on said rim, means actuated by said movement of said pressure members for causing said pressure members to move radially 70 outward to impart a polygonal form to said rim, a series of outer pressure members positioned around the outside of said rim, each of said outer pressure members being located between the paths of radial movement of two of said inner pressure members, and means for moving said outer pres- 75

sure members radially inward to press inwardly those portions of said rim which are located between said inner pressure members.

9. The combination in apparatus for forming a polygonal rim having a flare along one edge, of a 5 series of inner pressure members adapted to extend within and support a cylindrical metallic rim, said pressure members being flared at one edge transversely to the axis of said rim, means 10 for moving said pressure members and said rim longitudinally of the axis of said rim to cause said flared portions of said pressure members to produce an annular flare on said rim, means actuated by 15 said movement of said pressure members for causing said pressure members to move radially outward to impart a polygonal form to said rim, a series of outer pressure members positioned around the outside of said rim, each of said outer pressure members being located between the paths 20 of radial movement of two of said inner pressure members, and means for moving said outer pressure members radially inward to press inwardly those portions of said rim which are located between said inner pressure members, said outer pressure members being adapted to engage only 25 those portions of said rim which are removed from said flared portion.

10. The combination in apparatus for forming a polygonal flanged rim, of a series of radially 30 movable inner pressure members each having an angular outer edge corresponding to the angle between two sides of the polygonal rim to be formed, said pressure members being adapted to extend within and support an annular metallic rim having an inwardly extending flange along 35 one edge, a pressure plate adapted to engage said flange and move said rim and said pressure members longitudinally of the axis of said rim, and means actuated by said movement for effecting radial outward movement of said pressure mem- 40 bers.

11. The combination in apparatus for forming a polygonal flanged rim, of a series of radially 45 movable inner pressure members each having an angular outer edge corresponding to the angle between two sides of the polygonal rim to be formed, said pressure members being adapted to extend within and support an annular metallic rim having an inwardly extending flange along one edge, a pressure plate adapted to engage 50 said flange and move said rim and said pressure members longitudinally of the axis of said rim, a stationary spindle having inclined end surfaces, and means coating with said surfaces for effecting radial outward movement of said pressure 55 members during said longitudinal movement of said pressure plate.

12. The combination in apparatus for forming a polygonal flanged rim, of a series of radially 60 movable inner pressure members each having an angular outer edge corresponding to the angle between two sides of the polygonal rim to be formed, said pressure members being adapted to extend within and support an annular metallic rim having an inwardly extending flange along 65 one edge, a pressure plate adapted to engage said flange and move said rim and said pressure members longitudinally of the axis of said rim, means actuated by said movement for effecting radial outward movement of said pressure members, a 70 series of radially movable outer pressure members each having a path of movement midway between the paths of two of said inner pressure members, and means actuated by said longitudinal movement of said pressure plate for causing ra- 75

dial inward movement of said outer pressure members.

13. The combination in apparatus for forming a polygonal flanged rim, of means for holding the flange of a circular rim having an inwardly extending flange, and means for exerting pressure radially on said annular rim to impart to it a polygonal form while said flange is so held.

14. The combination in apparatus for forming a polygonal flanged rim, of a series of pressure members for engaging a cylindrical rim having an inwardly extending transversely corrugated flange, means for engaging opposite sides of said inwardly extending flange and holding it in one plane, and means for effecting radial movement of said pressure members to impart a polygonal form to said rim.

15. The combination in apparatus for forming polygonal rims, of an annular series of pressure members each having a face shaped to conform to an apex of a polygon, another annular series of pressure members arranged in staggered relation with respect to the pressure members of said first named series and each having a flat face adapted to conform to a side of said polygon, said two series of pressure members being normally spaced apart to permit a circular rim to be inserted between the two series, means for moving the pressure members of one series radially inward, and means for moving the pressure members of the other series radially outward, whereby said circular rim is converted into polygonal form. 5 10 15

ALLEN B. WILSON.
